UNITED STATES PATENT OFFICE

AUGUSTE MAGIS AND ANDRÉ HUET, OF PARIS, FRANCE, ASSIGNEES TO THE
SUPERHEATER COMPANY, OF NEW YORK, N. Y.

BOILER

Application filed January 5, 1929, Serial No. 330,468, and in France January 11, 1928.

The present invention has for its object the provision of a steam boiler so operated that the combustion gases do not change their direction anywhere in their upward course toward the stack except at the point where they are to be relieved of the dust and soot they may entrain.

In addition, the boiler is equipped with an air preheater in the upper portion of the gas path. The air flows at first in counter current through a main air heater, which may be metallic, where it is heated and then flows toward the furnace through a set of hollow chambers formed in the boiler walls where it serves to cool these walls and at the same time to take up the radiant heat from the brick work which is in contact with the high temperature gases coming from the furnace. By this means a very complete heat economy is obtained while at the same time the bricks lining the furnace and coming into contact with the hot gases are better preserved since they are directly cooled by constantly changing air. The invention is illustrated in the drawings, in which Fig. 1 is a vertical central section on line $y-y$ of Fig. 2, and Fig. 2 is a vertical section on line $x-x$ of Fig. 1.

In Figs. 1 and 2 which give an illustrative embodiment of our invention, the combustion chamber or furnace a of the boiler is shown as equipped for pulverized fuel. The vertical and horizontal walls are lined with water tubes in order to utilize as well as possible the radiant heat of the furnace.

The combustion gases coming from the chamber or furnace a rise to the tubular bundle b lying in the large vertical passage u .

The gases then pass over a superheater c and then over an economizer d both lying in the passage u above the vaporizing bundle b . On leaving the economizer they are subjected to a change in direction indicated by the arrows f shown in Fig. 2, this change being brought about by the baffles k and j . At the same time the free cross sectional area is properly altered so that the gases experience a sudden expansion whereby cinders and dust which may have been entrained are dropped in the corners g , g . These cinders may later on be removed through the open-

ings h provided for this purpose or in any other way, for example by blowing them out with compressed air or steam.

The gases having been thus cleansed proceed toward the air preheaters placed above the passage u at each side of the boiler and finally leave through the passages l , l . The air for supporting the combustion in the furnace enters at the top of the boiler by the orifices m , m , and flows in counter current, that is to say in a direction opposite to that of the gas flow, through the metallic heaters i , i , and flows in a heated condition through the orifices z , z , into the chamber o . This chamber is in communication with the hollow lateral walls p by means of the orifices q . The air circulates either freely or along a path determined by baffle r , for example arranged in an inclined manner through the interior of the hollow wall spaces, so as to form a downwardly directed passage from the inlet to the furnace said passage winding around the setting in the interior of the walls. It is thus conducted to the lower part of the combustion chamber from which it is introduced into the furnace through the orifices s .

It is quite evident that without departing from the scope of the invention, modifications may be introduced in the general arrangement of the parts relatively to each other. Thus, the dust and cinders contained in the gases may be deposited in corners such as g , g , before the gases pass into contact with an economizer, or there may even be several successive depositions of such cinders, for example one before the superheater, another before the economizer, etc.

The general arrangement of this boiler has the particular advantage that it makes possible the use of very simple masonry as illustrated in the drawings, and that the walls may be entirely vertical without arches except those used in the deposition of the cinders. The general construction of the boiler is therefore considerably simplified and the capacities of the several parts of the boiler can be made whatever is desired. Thus, the gas passages can be varied at will by short-circuiting a portion of the gas current by

means of simple dampers arranged either in the center of the tube bundles of the superheater or the other heat interchangers such as is shown, for example, in the center of Fig 2 at *t*.

5 We claim:

1. A boiler comprising in combination a high setting, a furnace in the lower part of the setting, a steam generator and a steam superheater arranged in said setting above the furnace and so that the gas flow through them is in a generally vertical direction, a chamber for receiving hot air directly above a portion of the generator and superheater, means cooperating with the lower and side walls of said chamber to give the gases a short horizontal travel followed by a sharp reversal back to a vertical path and adapted to form a pocket at the angle in the path of the gases whereby solids carried by the gases are dropped at this point, said means adapted also to direct the gases vertically along the side of said chamber; and air heating means arranged to contact with the gases 25 in their vertical flow at the side of said chamber and connected to deliver air into it.

2. A boiler comprising in combination a comparatively high setting having a furnace in its lower portion, a steam generator and a steam superheater directly above a portion of the furnace, a chamber for heated air directly above a portion of said superheater and generator, said chamber and said setting forming passages running one on each 35 side of the chamber, and air heating means in each of said passages connected to deliver air into said chamber, said setting having hollow walls providing passages which are connected to said chamber and arranged to deliver air into said furnace.

3. Boiler as set forth in claim 2 and in which baffle members are arranged to extend inwardly from the setting between the lower face of the air chamber and the top of the superheater.

4. Boiler having a furnace, a steam generator and a steam superheater arranged to receive heating gases from said furnace, a chamber for hot air arranged directly over a portion of the superheater and generator and a setting for the superheater and generator arranged to form passages, one on each side of the chamber, and conducting vertically combustion gases which have passed the superheater, air heating means in said passages connected to deliver air into said chamber, and connections for leading air from said chamber into said furnace.

5. A boiler having a high setting of uniform horizontal dimension in one direction and containing a furnace, a generator and superheater directly above a portion of said furnace, a chamber for heated air directly above a portion of said superheater and generator, passages for gases of combustion on both

sides of said chamber in the vertical plane which includes said constant horizontal dimension, said passages having each a horizontal portion and a vertical portion forming a sharp angle and arranged to form also 70 a pocket to separate cinders from the gases passing therethrough, and elements for heating air arranged in said passages, said setting having a less horizontal dimension in one direction at the top than at the bottom. 75
